Primary Examiner — Mary Ann Calabrese*Assistant Examiner* — Sloan Rozin(57) **CLAIM**

The ornamental design for a keyboard desk with guard board, as shown and described.

DESCRIPTION

FIG. 1 is a perspective view of the keyboard desk with guard board;

FIG. 2 is a front view thereof;

FIG. 3 is a bottom view thereof;

FIG. 4 is a top view thereof;

FIG. 5 is a rear side view thereof;

FIG. 6 is a left side view thereof; and,

FIG. 7 is a right side view thereof.

The broken line showing of elements on the keyboard desk with guard board illustrate portions of the article and form no part of the claimed design.

1 Claim, 7 Drawing Sheets(56)
